UNITED STATES PATENT OFFICE.

JOHN C. RYAN, OF DETROIT, MICHIGAN.

SKYLIGHT.

SPECIFICATION forming part of Letters Patent No. 286,558, dated October 9, 1883.

Application filed June 5, 1883. (No model.)

To all whom it may concern:

Be it known that I, JOHN C. RYAN, of Detroit, county of Wayne, State of Michigan, have invented a new and useful Improvement 5 in Skylight-Bars; and I declare the following to be a full, clear, and exact description of the same, such as will enable others skilled in the art to which it pertains to make and use it, reference being had to the accompanying 10 drawings, which form a part of this specification.

My invention consists in the combinations of devices and appliances hereinafter specified, and more particularly pointed out in the 15 claim.

In the drawings, Figure 1 is a vertical section of a device embodying my invention. Fig. 2 is a longitudinal section. Fig. 3 is a side elevation.

20 The object of my invention is to provide an improved skylight-bar whereupon the glass may be readily secured, and, if necessary, replaced, which shall be adapted also to prevent any dripping of moisture that may 25 gather upon the glass descending into the rooms beneath. I accomplish this object as follows:

In the drawings, A represents the central rib or bar of metal.

30 B and B' represent the troughs, preferably constructed of a single piece of sheet metal, compressed so as to fit over the upper edge of the rib and down upon each side thereof a suitable distance, and then bent into a suitable shape for a trough, the outer edges turned so as to form upwardly-extending flanges, b and b'. The bottoms of the troughs are perforated.

C is the lower channel, preferably constructed 40 of a single sheet of metal extending over the lower edge of the central rib, the edges extended upward and secured to the flanges of the troughs by being hooked longitudinally over the edges of said flanges, or in any other 45 suitable manner.

D represents a series of supports, preferably constructed of rubber or other elastic and suitable material. These supports may be of any suitable number, and may be loosely or 50 rigidly located in the troughs on both sides of the central rib, and are intended to receive the edges of the glass, dispensing with the ordinary process of putting the glass upon the skylight-bar.

55 E is the glass.

F is the cover, adapted to be secured in place by flexible strips a, of any suitable number, secured upon the central rib.

It is evident that when the glass is thus located in position and the cover is secured in place, the interior edges of the glass, resting upon the supports D, are hidden from view, while any moisture accumulating on the glass will tend to be discharged into the troughs B, passing thence through the perforations in 65 the bottom of the trough into the lower channel, C, whereby it will be conducted away from the skylight. I prefer that the supports should be of sufficient height to lift the glass off from the flanges of the trough, so as to 70 more effectually prevent the moisture from dripping down beneath the skylight. The supports may or may not have extensions d to prevent the edges of the glass from coming in contact with the metal.

75 It will be seen that a skylight-bar thus constructed will afford a perfectly water-tight support for the glass, while at the same time it is very simple, and the glass may be very readily secured thereon. Should a pane of glass 80 be broken, there is no necessity of first clearing off the hard putty and securing another pane in place by the application of putty.

I am aware that it is not new to construct a skylight-bar V-shaped in cross-section, with 85 transverse grooves in the upper edges of the ledges on which the glasses rest, the ledges being formed with longitudinal guttered depressions located within the V-shaped bar, and having perforations to permit the water 90 to pass under the glasses into the bar, the joints at the edges of the glasses being covered by a cap-plate. Such, therefore, I do not claim.

95 What I claim is—

In a skylight-bar, the combination, with the central rib, of a sheet of metal bent over the upper edge of the bar and shaped into a perforated trough on each side of the rib, a lower channel bent over the lower edge of the 100 central rib, and secured at its edges to said trough, and, in addition thereto, supports located in said troughs and a suitable cover, substantially as described.

105 In testimony whereof I sign this specification in the presence of two witnesses.

JOHN C. RYAN.
